UNITED STATES PATENT OFFICE.

JOHN McMYLER, OF CLEVELAND, OHIO.

CLAM-SHELL BUCKET.

No. 811,946.

Specification of Letters Patent.

Patented Feb. 6, 1906.

Application filed May 22, 1905. Serial No. 261,548.

To all whom it may concern:

Be it known that I, JOHN McMYLER, a citizen of the United States, residing at Cleveland, in the county of Cuyahoga and State of Ohio, have invented a certain new and useful Improvement in Clam-Shell Buckets, of which the following is a full, clear, and exact description, reference being had to the accompanying drawings.

10 The clam-shell bucket embodying this invention, as shown in the drawings, was designed with a special reference for use in unloading ore from the holds of vessels; but obviously it is adapted for any analogous uses.

15 The invention consists of the various combinations of parts constituting the mechanism for suspending the bucket-jaws and for opening and closing them by the use of ropes or cables.

20 In the drawings, Figure 1 is a side elevation of the improved bucket. Fig. 2 is a plan view thereof.

The bucket-frame is made up of four parallel vertical plates, which are held in fixed relationship by means of various transverse shafts and rods shown in the drawings. The two inside plates A A' are larger than the two outside plates B B'. The two bucket-jaws are indicated by C C'. The power-shaft 25 D extends horizontally through all four of these plates and is capable of rotating in bearings which those plates supply. Suitable drums, as d d', are secured to this shaft. The opening-ropes F are wound upon the 30 smaller drums, and the closing-rope H is wound upon the larger drum. From these drums the ropes pass upward in engagement with guide-sheaves J, J', and K.

Two levers E, having gear-segments e 35 formed on their upper arms, are hung upon the transverse shaft e', and these gear-segments are in mesh, respectively, with the pinions G, secured upon the power-shaft D, wherefore the rotation of that shaft in either 40 direction, by drawing upon the ropes F and H, would cause the rocking in one direction or the other of these segment-levers. The lower arm e' of each segment-lever is pivotally connected with an upwardly-extended 45 ear c at the rear end of the bucket-jaw C. Two bell-crank levers M are hung upon a transverse shaft m, which occupies a position at one end of the frame corresponding to the 50 position occupied by the shaft e' at the other end of the frame. One arm L' of each of these bell-crank levers extends down and is

pivotedly connected with an upwardly-extended ear c' at the rear of the bucket-jaw C'. The arm m' of each of these bell-crank levers is connected, by means of a link N, with the 55 corresponding segment-lever E.

The front end of each bucket-jaw is pivotally connected with two links P, one on each side thereof, and the two upper ends of these links are pivotally connected with the frame 60 at points above the rear ends of the buckets and preferably outside of the vertical planes of the axes of the shafts e' and m.

By drawing upward on the ropes F (the rope H being simultaneously slackened) the 65 power-shaft D is turned in that direction which swings the gear-segments downward. This movement swings the rear end of the bucket-jaw C outward and upward. The bucket-jaw C' is simultaneously moved in 70 like manner by the bell-crank levers M, which receive their motion from the segment-levers through the links N. The described movements of the rear ends of the two bucket-jaws cause of necessity some movement of 75 the front ends of said jaws, which movement is guided and determined by the links P. When the jaws are opened, they and the connected parts described occupy the positions indicated by the dotted line in Fig. 1. When 80 the operator pulls on the rope H and simultaneously slackens the ropes F, the described parts reverse their movement.

It will be noted that the power to open and close both bucket-jaws is applied at their rear 85 ends and is derived from the segment-levers. The links P transmit none of the power to move the jaws, but merely act as guides which compel the front ends of the bucket-jaws to spread wide apart when the rear ends 90 of said bucket-jaws are moved, as described. The result is when the bucket-jaws are opened they stand in substantially vertical positions. When they are closed, they first scrape the material together between them and then dig 95 under said material and fill themselves with it as they pass to the substantial horizontal position they occupy when closed.

I claim—

1. In a clam-shell bucket, the combination 105 with the frame, and two bucket-jaws, of levers pivoted to opposite ends of said frame and having depending arms which are pivotally connected with the upper rear ends of the bucket-jaws, means for swinging said lever-arms to move their depending arms toward and from each other, and links P pivot- 110

ally connected with the upper front parts of said bucket-jaws and with the frame at points above the rear ends of said jaws.

2. In a clam-shell bucket, the combination
5 with the frame, and two bucket-jaws, of levers pivotally connected with the said frame at opposite ends thereof and having depending arms which are respectively pivoted to the sides of the rear ends of said bucket-jaws,
10 mechanism operating on the levers at one end of the frame to rock them back and forth, a link connecting the levers at one end of the frame with the levers at the other end of the frame and transmitting motion from one to
15 the other, and links P pivotally connected with the sides of the front ends of said jaws and with the frame at points above the rear end of said jaws.
3. In a clam-shell bucket, the combination
20 with the frame, and two bucket-jaws, of the levers E E mounted in the frame at one end thereof, and having depending arms which are pivotally connected with the rear end of one bucket-jaw, the bell-crank levers M, M
25 mounted in the frame at the other end thereof and having depending arms which are pivotally connected with the rear end of the other bucket-jaw, means transmitting motion from the first-mentioned levers to said
30 bell-crank levers, mechanism mounted in the frame for rocking the first-mentioned levers,

and links P pivotally connected with the front ends of said bucket-jaws and with the frame at points above the rear ends of said jaws.

4. In a clam-shell bucket, the combination
35 with the frame, and two bucket-jaws, of gear-segments mounted on alined axes in one end of the bucket-frame and having depending arms which are pivotally connected with the rear end of one bucket-jaw, a power-shaft mounted in the frame and carrying pinions engaging said segments, bell-crank levers M M mounted on alined axes in the other end of said frame and having depending arms which
40 are pivotally connected with the rear end of the other bucket-jaw, links N connecting the horizontal arms of said bell-crank levers with the gear-segments, means for rotating the said power-shaft in either direction, and links
45 P having their lower ends pivotally connected with the front ends of the bucket-jaws and having their upper ends pivotally connected with the frame at points above the rear ends of said bucket-jaws.

55 In testimony whereof I hereunto affix my signature in the presence of two witnesses.

JOHN McMYLER.
